UNITED STATES PATENT OFFICE.

HORACE SEE, OF NEW YORK, N. Y.

DESIGN FOR A CASING FOR CONDENSERS.

SPECIFICATION forming part of Design No. 28,150, dated January 11, 1898.

Application filed August 25, 1897. Serial No. 649,536. Term of patent 14 years.

To all whom it may concern:

Be it known that I, HORACE SEE, of the city, county, and State of New York, have invented and produced a new and original Design for a Casing for a Condenser for Steam-Engines, of which the following is a specification.

Figure 1 is a top view, and Fig. 2 is an end view, of a condenser-casing exhibiting my design.

The body A of the casing is cylindrical. Near each extremity is a flange B, and beyond each flange heads C and C'. In the heads may appear one or more openings, as D, Fig. 2. The outer periphery of said heads may be rounded, as shown at D'. Projecting from the casing at E and F are legs which, when the casing is placed horizontally, extend downwardly at one side, as shown in Fig. 2.

On the upper side of the casing appear two circular flanged openings G H; also, a circular flanged opening I and a rectangular flanged opening J. On the periphery of the casing appears a projection O, as shown in Fig. 2. The end view of the head C exhibits two offsets or projections K and L. Flanges M N ²⁵ may appear around the body of the casing; but these are not essential to my design.

I claim—

The design for a casing for a condenser for steam-engines, substantially as herein shown ³⁰ and described.

HORACE SEE.
